(57) **CLAIM**

The ornamental design for an "motorcycle stereo mounting device," as shown and described.

DESCRIPTION

FIG. 1 is a perspective view or an auto stereo mounting device, showing my design;

FIG. 2 is a rear perspective view of FIG. 1;

FIG. 3 is a front elevation view of FIG. 1;

FIG. 4 is a rear elevation view of FIG. 1;

FIG. 5 is a bottom plan view of FIG. 1;

FIG. 6 is a top plan view of FIG. 1;

FIG. 7 is a right elevation view of FIG. 1; and,

FIG. 8 is a left elevation view of FIG. 1.

The broken lines shown in all views illustrate mounting features which form no part of the claimed design.
